Primary Examiner — Anhdao Doan*(74) Attorney, Agent, or Firm* — Scheinberg & Griner, LLP;
David Griner; Michael O. Scheinberg**(57) CLAIM**

I claim the ornamental design for a sample carrier, as shown and described.

DESCRIPTION

FIG. 1 is a perspective view of a sample carrier according to the present design.

FIG. 2 is a bottom view thereof.

FIG. 3 is a top view thereof.

FIG. 4 is a side view thereof. A view of the opposite side is a minor image of the side as shown.

FIG. 5 is a front view thereof; and,

FIG. 6 is a back view thereof.

The broken lines in FIGS. 1-5 are included for the purpose of illustrating portions of the sample carrier that form no part of the claimed design.
